[57] CLAIM

The ornamental design for a gambrel for game animals,
as shown and described.

DESCRIPTION

FIG. 1 is a front elevational view of a gambrel for game animals, showing my new design, the rear being a mirror image thereof;

FIG. 2 is a top plan view of FIG. 1;

FIG. 3 is a bottom plan view of FIG. 1; and,

FIG. 4 is an end elevational view of FIG. 1, the opposite being a mirror image thereof.
